UNITED STATES PATENT OFFICE.

NICOLAS JOSEPH GALLAND, OF PARIS, FRANCE.

SYSTEM OF MALTING AND APPARATUS EMPLOYED THEREIN.

SPECIFICATION forming part of Letters Patent No. 241,958, dated May 24, 1881.

Application filed April 27, 1878. Patented in England, No. 1,988 of 1874, and No. 2,825 of 1876; in France June 2, 1874, in Belgium June 4, 1874, in Alsace-Lorraine June 10, 1874, in Austria August 31, 1874, and in Bavaria December 12, 1874.

To all whom it may concern:

Be it known that I, NICOLAS JOSEPH GALLAND, of Paris, in the Republic of France, have invented certain new and useful Improvements 5 in the System of Malting and the Apparatus Employed Therein, of which the following is a full, clear, and exact description, reference being had to the accompanying drawings, forming part of this specification.

10 The transformation of barley into malt is usually effected by these distinct operations, viz., steeping, germination, and drying or kiln-drying.

15 To obtain a malt of even quality it is not only necessary to use barley of regular growth, but, during its steeping and germination, every part of the grain must have contact with pure air of an even degree of humidity and heat.

20 My invention relates particularly to the operations of steeping and germinating; and it consists, mainly, in causing a current of air to be drawn through the mass of grain during its treatment, which current of air is maintained at the proper temperature by passing it through 25 a mass of broken stones, coke, and the like, which is kept damp by means of well-water.

The invention further embraces modifications and an improved apparatus.

20 The method generally practiced of steeping barley by successive immersions during forty-five to sixty hours is believed to have three defects, viz: First, the suffocation of some stunted grains; second, the dissolution of about one-half of the useful component parts of the 35 grain, which are carried off by the steeping-liquor; and, third, in more thoroughly steeping or soaking the grains at the bottom of the vat than those at the top, on account of the difference in the pressure of the steeping-liquor.

40 To avoid these defects I employ for steeping very flat or shallow stationary vats, as A, Figs. 1, 2, 3, and 4, in which the thickness of the layer or bed of barley is not over fifty centimeters, whereby the light grains are permitted 45 to rise to the surface with great facility, and the pressure of the steeping-liquor on the barley of good quality is so diminished that the water or steeping-liquor may be left six to eight hours on the grain without stirring the mass.

50 When the water (if water is used, as is com-

monly practiced, as the steeping-liquor) is once drawn off, it is only necessary to sprinkle the barley at regular intervals and to stir it well with the shovel. The grain then readily absorbs this sprinkling-water without being deprived of the requisite contact with the air. It swells up in the desired time and no useful substance is carried off, as is the case in the ordinary method. Such an operation, however, requires considerable labor, and in order to 60 obviate or lessen this I provide said shallow steeping-vats with perforated false bottoms or supporting-plates B, suitably fixed about ten centimeters above the bottom proper, M, of such vats, which plates properly support the thin 65 bed or layer of grain and admit the passage of a current of air through the grain during the intervals of sprinkling the same. This current of air is caused to pass from above through the layer of grain, as is indicated by the arrows 70 N, (see Fig. 4,) and may be generated by any common motor, whereby a current of air is drawn through a conduct-pipe, as m, which, communicating through the plate B with the chamber between it and the bottom M of the 75 vat, causes the air to pass through the grain in the vat and thence to find its exit through the pipe m. This current of air may be controlled by means of a damper, as x, with which the pipe m is provided. (See Fig. 4.) This current of air may be used after the first steeping of about six hours' duration is finished, and it is drawn through the mass of grain, and thoroughly ventilates the same by supplying oxygen and carrying off the carbonic-acid gas 80 which is formed and given off by the grains, so that after forty to sixty hours, when the grain is sufficiently soaked with water, it may remain three days in the steeping-vat without being stirred; but after three days the germination of the grain will have been so far effected that its rootlets will have become so long as to intertwine and felt the whole mass together, thus stopping up the holes in the plate B and preventing the passage of the current of air. 85 It is then necessary to empty the grain into proper receptacles for finishing its germination. This may be accomplished by removing a plug, o, Fig. 4, from the mouth end of a discharge-pipe, as n, with which each vat is supplied, and 90 95 100

which extends through the bottom plate, M, and the supporting-plate B of said vat. This pipe *n* may lead to a stationary germinating-vat, as D, Figs. 1, 2, 3, or to a rotating germinating-drum, C, (shown in detail in Fig. 6,) which germinating-vats or drums are suitably placed on the floor beneath the steeping-vats, and arranged in proper series, as will be more fully hereinafter explained.

10 The steeping alternating with ventilation just described as carried on in shallow vats gives very good results; but about three fourths per cent. of the soluble substances of the grain is still lost, and if the sprinkling is followed 15 by shoveling the grain over for equalizing the moisture the labor involved is necessarily considerable.

To avoid these defects the steeping may be done in rotating cylindrical drums A', Fig. 5.

20 These drums are constructed of two heads, O P, centrally perforated, and properly flanged to receive the ends of and support an exterior casing or cylinder, C³, and an interior central cylinder, C², which cylinders are perforated to 25 admit the passage of air. These drums are provided with an opening, Q, to the chamber formed between the cylinder C³ and the cylinder C², which opening is closed by any common means, as a cap or door provided with suitable 30 fastenings, and serves to admit of the introduction or discharge of the grain. The heads of the drum are properly shaped, so as to constitute wheels, or the body of the drum is provided with rings acting as wheels, whereby it may 35 rest and be revolved upon rollers B². It is supplied with an air-pipe, E', connected to the cylinder C² by a packing-box, so as not to obstruct the revolving of the drum, which revolving may be accomplished by any common means. This 40 air-pipe E' also connects with an air-motor, in like manner as does the pipe *m*. It is also provided with an injector-pipe, D', which enters the end of the cylinder C², whereby the grain may be sprinkled with water at pleasure.

45 The grain is introduced through the opening Q into this steeping-drum, which opening is then closed and the said drum is slowly revolved. At the beginning of the operation the grain is moistened. After an hour this moistening is followed by a very abundant sprinkling of water, which carries all the substances 50 adhering to the surface of the grain to the trench F². After this washing it is sufficient to give the grain the quantity of water necessary to swell it up. After remaining five days in these drums, for steeping and preliminarily germinating the grains, the barley is emptied through the opening Q, and directed, by a suitable conduit-pipe, as in the case of the stationary shallow vats, into the fixed germinating-

60 cases D, or into the rotating germinating-drums C, which, as before stated, are located on the floor below. These steeping-drums A' are more expensive than the shallow vats A, but 65 their operation is more perfect, and they are also capable of use as germinating-drums in

like manner as are the rotating germinating-drums C, yet to be explained.

Germination of the grains is produced under the influence of water and oxygen of the air, which, combining, in the presence of water, with the carbon of the grain, produces carbonic-acid gas with disengagement of heat. Under this influence the rootlets come out of the grain, and the future stem advances within the husks.

To produce these phenomena under the most favorable circumstances is the principal object of the malster. For this purpose, in ordinary malting, the barley when sufficiently steeped is then spread in thin layers on the germinating-floor.

The grain becomes warm, and air must be given to the young plant to remove the carbonic-acid gas and the heat, which would be generated under disastrous conditions if not regulated by repeated turning over day and night, which must be done by skillful hands.

The malster cannot always guard against great irregularities in his malt. A number of the grains are crushed by the feet of the workmen, and these grains, as well as those which do not germinate, become moldy, and it is fortunate if the whole mass is not too much heated through negligence.

In practicing the ordinary process the malster operates without much difficulty in temperate climates from September to May—that is to say, during the months when the average temperature is not over 12° centigrade. In winter the malster is often troubled by frost, which obliges him to smother his malt by closing the ventilating-shutters, while in summer he must discontinue work altogether. Thus over four months of the year are lost, a discharge of his men becomes necessary, while the expenditure of a large amount of capital has been involved in filling his stores, and his surplus raw materials are liable to become destroyed either by the attacks of insects or by the absorption of moisture.

Impressed by these defects in the common system of malting I have succeeded in devising a rational process, which can be carried on with regularity during the whole year, for the reason that it is operative independently of the fluctuations of the temperature of the air, which system I call "pneumatic malting," and which, compared to the old system, realizes great economy in labor, cost of plant and working capital, while at the same time easily producing uniform malt of first quality and minimum acidity.

In carrying said process into effect I use for regulating the temperature well-water, which in temperate climates is nearly everywhere found at from 10° to 12° centigrade in ordinary wells.

My process consists in placing the barley previously steeped by the common means, or by one of the methods hereinbefore described, either into vats, as D, or into the revolving drum C, Figs. 1, 2, 3, and 6, and to submit it therein to a regulated ventilation by causing

a current of fresh and humid air to pass around each grain, by which means the barley is maintained at the required low temperature, and is enabled to pass through the different stages of germination without accident. The air is drawn through the mass of grains, (instead of being forced through the same,) and while passing regularly through the layers of grain from top to bottom and cooling them, carries with it the disengaged carbonic-acid gas, which is much heavier than the air. The air thus traversing the grain performs four functions, viz.: First, it supplies the oxygen, and, second, the moisture, both being necessary for the respiration of the grain in going through the chemical process of germination; third, it cools the germinating mass, and, fourth, it carries off the carbonic-acid gas which is produced.

The respiration of the germs requires but little oxygen, which can be supplied by a feeble current of air; but the quantity of heat generated by germination must be absorbed by a very considerable quantity of fresh air, considering the low specific heat of the air and the slight difference of temperature it must have (a few degrees only) between its entering the grain and its leaving it, for, to yield good malt, the grain should not during germination have a higher temperature than the mean temperature of 15° or 16° centigrade. If the large volume of fresh air necessary for cooling the layers of grain were not saturated with moisture it would finally cause the grain to wither, if not to be desiccated, and thus modify or destroy the conditions favorable to germination.

In order to properly supply the air with moisture and the humid air with regularity, I have devised an apparatus in which to carry out my system of malting, which I will now describe.

The malt-house, which is a closed structure, may be of any form, that of a rectangle shown being a good one, and constructed of any materials, masonry being preferred. At one end this house has an air-induction opening or passage, E, which will be supplied with a closing-door, the purpose of said opening or passage being to supply from time to time the necessary amount of fresh air. Above this opening, and within its outer wall, this house is provided with one or more filter-chambers, H, Figs. 1 and 2, which I call "coke-towers." They are preferably built of masonry and of suitable dimensions. Their lower ends are provided with grates I, and they are nearly filled with pieces of coke or broken stones, while near their tops these coke-towers open directly into the interior of said house by means of flues S'. These towers are also provided at their upper ends with shower-pipes, as S, which pipes communicate with the wells or tanks of the establishment and supply a constant shower of water upon the coke. At the opposite end of the house there is a chimney, W, provided with a damper or valve, K', which communicates di-

rectly with the base of the coke-stack and the opening E by an auxiliary flue or conductor, F', that extends longitudinally underneath the floor U, which flue is provided with a valve, K'. 70 Beneath this auxiliary flue or conductor F' is a main flue or conductor, F, closed at both ends, but communicating with the chimney W by means of a fan, rotary engine, or other air-motor, G, which has its induction-orifice in the flue F, and its eduction-orifice at the end of the flue F', in the said chimney W.

The steeping apparatus, whether in the form of the shallow fixed vats A, Figs. 1 and 4, or the rotary drums A', Fig. 5, is supported in 80 the upper part of the house upon transverse beams V, or upon longitudinal girders Z, or both, or upon a perforated flooring, in such manner that there may be a free movement of the air around them and throughout the whole interior 85 of the house and the germinating apparatus, whether in the form of stationary vats, as D, or rotating drums C, Figs. 1, 2, 3, and 6. The vats D may be sunk into the floor U, while the drums C rest thereon.

In one arrangement shown the air-pipes m, with which the fixed shallow vats A are provided, as heretofore described, lead to and communicate with the main flue or conductor F, as shown in Fig. 1, and their discharge-pipes 95 n lead to the fixed germinating-vessels D, (see Figs. 1 and 3,) and these germinating-vessels D, being constructed as are the steeping-vats A—that is, having perforated false bottoms B, (see Fig. 1,)—communicate directly with said 100 flue or conductor F by openings J, (see Figs. 1 and 3,) which openings may be regulated by a gate, t. In another arrangement the steeping-vessels are rotating steeping-drums, constructed as is shown in Fig. 5, and has been 105 heretofore explained, said drums being mounted in the positions occupied by the steeping-vats A, with their pipes E' communicating, as do the pipes m, with the flue F, but also connecting with the revolving germinating-drum 110 C. These germinating-drums C, Fig. 6, are constructed of two circular heads, a b, the former being centrally perforated to communicate with the short pipe G', to which heads are attached an exterior perforated sheet-metal cylinder, d, 115 and an interior perforated sheet-metal cylinder, R. The outer cylinder, d, has an opening, C', closed by a suitable cover.

A number—four to six—of longitudinal bars T, with their extremities turned at right angles 120 for securing them to the heads a b, each have riveted to them fingers L, which act as lump-breakers for dividing the mass of grain as the germinating-vessel revolves and the mass assumes the inclination X to Y.

The interior cylinder, R, is provided with solid partition-plates e', whereby it is divided longitudinally into a number of compartments. This cylinder R communicates, through a short pipe, G', with the pipe E', the head a being provided 130 with a collar, i, that receives the end of said pipe G', which arrangement permits the vessel

to revolve without disturbing said pipes G' and E' . This pipe G' is provided with a number of rotating screens, r , one for each of the compartments of said cylinder R , constructed so that the size of the passage from the pipe E' to one or all of the said compartments may be varied, or even entirely closed, so as to regulate the ventilation or suppress it, the proper movement of said screens being accomplished by suitable handles, only one of which is shown in Fig. 6. This pipe E' is provided with a register, J' , and communicates with the air-flue F . (See Fig. 3.) It also extends upward and communicates with the steeping-vat A , said communication being controlled by a valve x , as in the case of the pipe m . This construction admits of the shutting off communication with the drum C , so that a direct action with the steeping-vat A , or the steeping-drum A' , (if such drums are used instead of the vats A ,) may be obtained; or, by closing the valve x and properly opening the register J , action with the germinating drum C may be had. This drum is provided with proper means, as the rings u , for supporting it on rollers, as B^2 , so that it may turn thereon, and it may be supplied with any means for rotating it, as the toothed wheel e and driving-pinion p , its revolutions being almost imperceptible—that is, from two to four rotations per hour.

The grain to be steeped is placed in the stationary steeping-vats A or in the rotating steeping-drums A' , Fig. 5, (if such are preferred,) and the grain which has passed through ventilation and moistening, as before explained—that is, preliminarily steeped—is conveyed, as before explained, from the steeping-vessels into the fixed germinating-cases D , where it is systematically turned over by hand-labor, or into the revolving drum C , where the turning over is done mechanically. The air enters the malt-house through the opening E , and thence passes through the coke-tower upward from the bottom to the top, against the fresh well-water, which is constantly showered by the pipe S upon the contents of the coke-tower, and throughout which it is distributed. The air then passes to the germinating-hall through the openings S' . It is then, by the motor G , drawn into the flue F after having passed in a downward direction through the beds or masses of grain placed in either of the vessels heretofore described. From the flue F the motor G draws the air for discharging it out through the chimney W , the valve K' being closed and the damper K^2 being opened.

The object of the coke-tower is to filter the air, to cool and to moisten it. The air for cooling the beds of grain traverses the filter in a direction opposite to that taken by the water, and in so passing in contact with the water takes its temperature and is saturated with moisture. In winter the temperature of the air is thus raised by contact with the water, while in summer it is in the same manner lowered, and as the water from the wells is at a con-

stant temperature, or about constant, during the whole year, it follows that the temperature of the air will be easily regulated thereby, and that by its use a regular germination will always result; but as the temperature of the external air varies considerably, not only from one season to another, but between day and night during all seasons, it is desirable to be able to regulate the influx of fresh air at pleasure, so as not to waste water, and because of the dust which chokes the coke-filters. It is sufficient to supply the quantity of oxygen necessary for the respiration of the germinating grain. Under the influence of the motor G the air contained in the working-halls passes through the steeping-vessels or germinating-drums, as the case may be, and enters the main flue or collector F , whence it again enters the motor G , which discharges it, if the damper K^2 is open and K' closed, into the chimney, or, said damper K^2 and the opening E being closed and K' opened, forces it through the flue F' , to be regenerated and cooled in the coke-tower and again caused to make the transit described.

A simple examination of the arrangement of the registers shows that the absorption and the distribution of the air may be made systematically variable and regulated.

The extreme registers—that is, the door controlling the opening E , and the damper K^2 controlling the opening into the chimney—can be closed partly or entirely, as may also the valve K' , so as to several times, in part or wholly, use the air contained in the halls by constantly regenerating it. By partially closing the opening E , the damper K^2 , and the valve K' , a fixed quantity of air only is admitted, and the same quantity of vitiated air is discharged.

The malster can vary the temperature of the air at will by regulating the quantity of water which is showered upon the coke-filter and by regulating the quantity of air passing through the grain. For the water this is done by stop-cocks in the shower-pipes S , and for the air by the gates, dampers x in the pipes m of the steeping-vessels, the gates t applied to the germinating-vats D , or the valves J' applied to the germinating-drums C .

To render the mass of grain in the vessels more permeable to air it may be transferred by the shovel from one into another at fixed intervals of time, according to the age of the bed, but not over twice in twenty-four hours. To facilitate this operation the vessels are arranged in as many series of three, five, or seven as the duration of the process continues in days, each series containing the work of twenty-four hours. One vessel in each series is always empty to receive the contents of the others, and the number of vessels in each series will be determined by the magnitude of the establishment. If the vessels are made very large the shoveling may be done in the vessel itself by partitioning it off and keeping one space vacant. Such a disposition of the cases reduces the labor of the ordinary operation

one-half; but in countries where labor is scarce and expensive it is important, particularly for large establishments, to reduce its cost as much as possible by substituting for it a mechanical power. This is accomplished by the use of my revolving drums, Figs. 5 and 6, the grain steeped while undergoing ventilation and mechanical turning in the one, being discharged into the other on the floor below, wherein its germination is completed while mechanically ventilated and stirred.

The malt-house is provided with an opening and roadway for a car, O, which may be run in under the germinating-drums to receive the malt therefrom when it is desired to remove it, the said malt being discharged directly into the car through the openings C'; but this roadway will, of course, be closed by a suitable door when the pneumatic process is being proceeded with.

What is claimed is—

1. The process of moistening and tempering air and employing it in malting, which process consists in drawing a current of air into contact with a quantity of coke, broken stone, and the like, which is moistened with well-water, and then passing the air thus moistened through the mass of grain undergoing treatment, substantially as described.

2. In a malt-house, a series of steeping-vessels arranged upon an open floor, in combination with a series of germinating-vessels arranged beneath them, the former being provided with means for discharging their contents into the latter, substantially as described.

3. In germinating grain in the production of malt, the process of ventilating the grain, which consists in passing a current of cooled and humid air from above downwardly through the mass of grain under treatment, whereby the natural gravity of the carbonic-acid gas which is generated is utilized in carrying it off, substantially as described.

4. The combination, with the coke-stack or filter, of the main and auxiliary air-flues F and F', the air-passages, and valves or dampers controlling them, whereby fresh air may be introduced and vitiated air simultaneously discharged, substantially as described.

5. The combination, with the perforated cylinders C² C³ of the rotating cylindrical steeping-drum, of an air-pipe, E', and a sprinkling-pipe, D', substantially as described.

6. The combination of the tower H, having tower inlet-opening E and upper outlet-opening, S', with the shower-pipe S, flues F F', motor G, and flue W, substantially as herein shown and described.

7. The combination of the vat A and its pipe m with the flue F, motor G, flue W, dampers k' k², flue F', tower H, and sprinkler-pipe S, substantially as herein shown and described.

8. The combination of the vat D, having false perforated bottom and opening J beneath the same, with the flue F, motor G, flue F', dampers k' k², tower H, and sprinkling-pipe S, substantially as herein shown and described.

9. The rotating germinating-drum C, in combination with the inner pipe, R, bars T, and fingers L, substantially as herein shown and described.

10. The combination of the rotating germinating-drum C and its pipe R with the pipe E' and screens r, substantially as herein shown and described.

11. The combination of the rotating germinating-drum C, its central pipe, R, bars T, and fingers L with the pipe E', flue F, and motor G, substantially as herein shown and described.

In testimony whereof I have signed my name to this specification in the presence of two subscribing witnesses.

NICOLAS JOSEPH GALLAND.
